UNITED STATES PATENT OFFICE.

FRITHIOF GUSTAF ERICSON, OF TORONTO, ONTARIO, CANADA.

LANDING-GEAR CONSTRUCTION OF AEROPLANES.

1,268,333.

Specification of Letters Patent. Patented June 4, 1918.

Application filed January 25, 1918. Serial No. 213,773.

To all whom it may concern:

Be it known that I, FRITHIOF GUSTAF ERICSON, a subject of Great Britain, of the city of Toronto, in the county of York, in the Province of Ontario, Canada, have invented certain new and useful Improvements in Landing-Gear Construction of Aeroplanes, of which the following is the specification.

10 My invention relates to improvements in landing gear construction of aeroplanes and the object of the invention is to simplify the construction of the connecting means between the front and rear struts of the 15 landing gear and yet provide such a means as will be rigid, strong and durable and at the same time cheap and readily constructed and it consists essentially of the following arrangement and construction of parts as 20 hereinafter more particularly explained.

Figure 1, is a sectional view through a landing gear showing my connection between the front and rear struts.

Fig. 2, is an end elevation of the parts 25 shown in Fig. 1.

Fig. 3, is an enlarged perspective detail of the connecting means between the front and rear struts.

Fig. 4 is a perspective view of the block 30 to which the knee plates are secured; the knee plates being shown in dotted lines.

In the drawings like letters of reference indicate corresponding parts in the various figures.

35 1 indicates a landing gear which is provided with the usual axle 2. 3 and 4 indicate the struts of the landing gear. Heretofore the lower ends of these struts have been connected together by a single bracket 40 which is complex in construction, expensive and difficult to make. In order to dispense with this bracket and cheapen and simplify the construction I have provided the following device.

5 indicates a block, which is of knee form 45 and provided with inwardly inclined ends 5^x and 5' to conform with the direction of the struts 3 and 4. 6 and 7 indicate knee plates, which are suitably secured at each side of the block 5 by bolts 8 which extend 50 through the plates 6 and 7 and through the block 5. The ends of the plates 6 and 7 are bent in any suitable manner to conform to the shape of the knee block 5 so as to conform to the direction of the struts 3 and 4 55 and are extended beyond the ends of the knee blocks to form sockets into which the ends of the struts 3 and 4 extend forming a butt joint with each end of the knee block 5. The struts are secured in position by 60 bolts 9 and 9^x, which extend through the plates 6 and 7 and through the ends of the struts 3 and 4 intervening between the extended ends of the plates 6 and 7.

From this description it will be seen that 65 I have devised a simple device by which the front and rear struts of an aeroplane landing gear may be securely connected together dispensing with all complex brackets and merely employing a block and side plates of 70 very simple and cheap construction.

What I claim as my invention is:

In combination with the downwardly converging front and rear struts of an aeroplane landing gear, a block having a knee 75 form providing portions upwardly diverging from near the center of the block, said portions having their end faces inclined and convergent upwardly to form butt joints with the ends of the struts, plates extending 80 along the sides of the block and beyond the same with means for securing said plates to the block and to the ends of the struts, substantially as described.

FRITHIOF GUSTAF ERICSON.
